United States Patent Office.

JAMES ARMSTRONG, OF BUCYRUS, OHIO.

Letters Patent No. 81,972, dated September 8, 1868.

IMPROVEMENT IN STEAM-GENERATORS.

The Schedule referred to in these Letters Patent and making part of the same.

TO ALL WHOM IT MAY CONCERN:

Be it known that I, JAMES ARMSTRONG, of Bucyrus, in the county of Crawford, and State of Ohio, have invented a new and useful Improvement in Steam-Boilers; and I do hereby declare that the following is a full, clear, and exact description thereof, reference being had to the accompanying drawings, in which—

Figure 1 is a front view.

Figure 2 is a side elevation.

Figure 3 is a rear elevation.

Figure 4 is a transverse section, taken in the line $x\ x$ of fig. 2, and

Figure 5 is a vertical section, taken in the line $y\ y$ of fig. 1, showing the manner of connecting the tubes. In all the figures the outer casing of the boiler, which fits over the outer tubes, is not represented.

The nature of my invention consists in the arrangement of the tubes which contain the water, by which a large surface is presented to the action of the heat from the fire, thereby causing a more rapid and economical generation of steam, and not so liable to explode as the ordinary flue or tube-boilers; also, in the manner of connecting the said tubes.

To enable others skilled in the art to make and use my invention, I will proceed to describe its construction and operation.

The front of the boiler is made of tubes or pipes, A, which are arranged vertically side by side, and at the lower and upper ends of the said tubes or pipes are horizontal tubes or pipes, B B', and are secured together by hollow screws, α , as seen in fig. 5.

The rear end of the boiler is of the same construction, with the exception that there is no horizontal tube or pipe at the bottom of the vertical tubes or pipes, but the sections of tubes are held together by a clasp, seen in figs. 2 and 3, and that the lower end of each vertical tube or pipe is closed by a screw-cap or plug, b .

The ends of the boiler are connected together by horizontal tubes or pipes, D D'. The outer ones, D, that form the shell, are placed closely together, but the inner ones, D', are made smaller, thus leaving a space around all the interior tubes or pipes for the fire and heat to circulate freely.

These horizontal tubes are secured to the vertical ones in the same manner as the latter are secured to the horizontal ones B B' on the ends of the boiler.

The fire-box is also formed of the tubes, which are connected together in the same manner as the others, as seen in the drawings.

By constructing a boiler in the above-described manner, any of the tubes can be cleaned, by removing one of the hollow screws or screw-caps. It will be seen that each tier of horizontal tubes connected by the vertical ones forms a section, and by removing the screws α in the horizontal cross-tubes B B', a section of the boiler can be removed, and by inserting screw-plugs into the openings left in the horizontal cross-tubes, the removal of a section does not interfere with the working of the boiler.

If desired, glass can be inserted in the screw-plugs, by which means the height of water can be ascertained, as seen in fig. 1 at c .

Openings are left at proper places, for the introduction of water and escape of steam.

Having thus fully described my invention, what I claim, and desire to secure by Letters Patent, is—

1. The arrangement of the outer and inner tubes of the boiler, whereby the heat is caused to circulate around the inner ones, substantially as shown and described.
2. The construction of the fire-box with the surrounding tubes, as herein shown and described.
3. The construction of the hollow screws α , and the arrangement of them with the tubes B, as herein shown and described.

JAMES ARMSTRONG.
